US00D922227S

(12) **United States Design Patent** (10) Patent No.: **US D922,227 S**
(45) Date of Patent: **** Jun. 15, 2021**

(54) **SIGNAL MEASURING APPARATUS**

(71) Applicant: **Proceq AG**, Schwerzenbach (CH)

(72) Inventors: **Sandra Riedewald**, Fribourg (CH);
Marcel Poser, Oberuzwil (CH);
Christopher Gordon Udell,
Ennetbaden (CH); **Michael Geiser**,
Zürich (CH)

(**) Term: **15 Years**

(21) Appl. No.: **35/507,342**

(22) Filed: **Apr. 24, 2019**

(80) **Hague Agreement Data**

Int. Filing Date: **Apr. 24, 2019**

Int. Reg. No.: **DM/202446**

Int. Reg. Date: **Apr. 24, 2019**

Int. Reg. Pub. Date: **Aug. 30, 2019**

(30) **Foreign Application Priority Data**

Dec. 13, 2018 (CH) 144387

(51) **LOC (13) Cl.** **10-04**

(52) **U.S. Cl.**

USPC **D10/83**

(58) **Field of Classification Search**

USPC D10/46, 52–56, 83, 84, 104.1,
D10/106.1–106.95, 108, 121, 123–125

CPC G01N 29/22; G01N 29/226

(57) **CLAIM**

The ornamental design for a signal measuring apparatus, as shown and described.

DESCRIPTION

2 Signal measuring apparatus

2.1 : Perspective

2.2 : Perspective

2.3: Front

2.4: Left

2.5: Top

Any views not disclosed in the drawings form no part of the claimed design.
